A. L. BREITENSTEIN

SCISSORS SHARPENER

Filed Feb. 29, 1924

FIG.-1.

FIG.-2.

Inventor

ARTHUR L. BREITENSTEIN.

By *A. L. Breitenstein*
Attorney.

UNITED STATES PATENT OFFICE.

ARTHUR L. BREITENSTEIN, OF AKRON, OHIO.

SCISSORS SHARPENER.

Application filed February 29, 1924. Serial No. 695,985.

To all whom it may concern:

Be it known that I, ARTHUR L. BREITENSTEIN, a citizen of the United States, and a resident of Akron, county of Summit, State 5 of Ohio, have invented certain new and useful Improvements in Scissors Sharpeners, of which the following is a specification.

This invention relates to a simple device by means of which scissors or shears may be 10 quickly and accurately sharpened, one of the objects of the invention being to provide a device of the character which is simple and inexpensive in construction and so designed that in use the scissors will be accurately 15 sharpened upon their angular faces.

In the drawings is shown one form only of the invention, it being understood that other forms may be devised within the scope of the appended claims.

20 In the drawings:

Fig. 1 is a view of the device with the two blades of the scissors shown in section and in position for use, and

Fig. 2 is a view at right angles to Fig. 1 showing the scissors in side view.

In the manufacture of the preferred form of the invention, which is illustrated here, a strip of flat steel or other metal is provided which is bent in general U-shape to 30 form a handle having arms 1 and 2. The arm 1 is provided with an extension 3 which is bent reversely or toward the handle portion so that its outer surface 3^a is in line with the inner surface 2^a of the arm 2. 35 When the scissors are placed in position for sharpening, the surfaces 2^a and 3^a operate as bearing surfaces of the flat sides of the scissor blades.

The arm 2 is provided with a lateral offset 40 portion 4, and in this portion and the arm 1, in position so that it spans the opening of the handle, is arranged the abrading or sharpening element 5, at the correct angle to the surfaces 2^a and 3^a. The part 5 may be 45 of any suitable substance, preferably hardened and roughened steel.

In the operation of the device the user inserts the part 5 between the blades of the shears, and with the flat surfaces of the blades against the surfaces 2^a and 3^a, moves the device in and out of the shears opening and closing them during the process. The guiding surfaces and the angular arrange-

ment of the element 5 insure a proper grinding of the scissor blades.

The invention is capable of embodiment in different forms from that specifically shown and described, and the claims should therefore be construed to cover such modifications.

I claim:

1. As a new article of manufacture, a scissor sharpener comprising a single strip of flat metal, the major portion of which is formed as a U-shaped handle, a piece of 65 abrading material extending across the outer end of the handle, and an extension on one arm of the handle, the outer surface of which is parallel to the inner surface of the opposite arm of the handle. 70

2. As a new article of manufacture, a scissor sharpener comprising a piece of metal, the major portion of which is bent upon itself to form a U-shaped handle, a piece of abrading material fastened in one 75 arm of the handle and extending across the handle and secured in the other arm, the second arm having a reversely bent extension parallel to the first-named arm and forming therewith bearing surfaces for the 80 flat sides of the scissor blades.

3. As a new article of manufacture, a scissor sharpener comprising a piece of flat metal, a portion of which is bent upon itself to form a U-shaped handle, one arm of said 85 handle having an extension bent upon itself so as to be parallel with the other arm of the handle, and a piece of abrading material secured in the handle at an angle to the arms. 90

4. As a new article of manufacture, a scissor sharpener comprising a strip of flat metal, a portion of which is bent upon itself to form a U-shaped handle, a lateral offset in one arm of the handle, the other arm of 95 the handle being provided with an extension which is reversely bent toward the handle, the outer surface of the extension and the inner surface of the first-named arm constituting bearing surfaces for the flat sides 100 of scissor blades, and a piece of abrading material arranged at an angle to said bearing surfaces and secured in the lateral offset and in the second-named arm.

ARTHUR L. BREITENSTEIN.
